UNITED STATES PATENT OFFICE.

LEE R. TITCOMB, OF BROOKLYN, AND HARRY S. ASHMUN, OF NEW YORK, N. Y.

PIPE-CLEANING DEVICE.

Application filed July 7, 1926. Serial No. 120,974.

This invention relates to a new and improved form of pipe cleaning device.

One of the objects of this invention is to provide a pipe cleaning device adapted to be 5 positively impelled in a pipe or sewer which is to be cleansed, by the propulsive action of a body of water which is forced through and out of the device and acts as wash water to remove the loose deposit or the like.

10 Another object of this invention is to provide a device of this type in which a body of water forced through and out of the device operates to produce a positive mechanical traction, so that it is not necessary to merely 15 rely upon the reaction of a part of the water forced through the device, after it has been rearwardly deflected.

Another object of this invention is to provide a device of this type in which all or any 20 desired portion of the body of water which is forced through the device can be caused to travel solely in the direction of the desired movement of the device.

Other objects of this invention will be set 25 forth in the following description and drawings which illustrate a preferred embodiment of this invention, it being understood that the above general statement of the objects of our 30 invention is intended merely to generally explain the same and not to limit it in any manner.

Fig. 1 is a front elevation partially in section.

Fig. 2 is a front elevation of the mouth of 35 the device.

Fig. 3 is a detail end elevation of the device, and it is partially in section.

Fig. 4 is a side view of one of the tractor 40 elements.

The device comprises a nozzle 1 made of any suitable metal and this is connected to an ordinary flexible hose by means of a coupling 3 which may be of any suitable type. The nozzle 1 may be provided with lateral openings 4 which, however, are not necessary for the operation of this invention. At the front thereof the nozzle 1 is provided with three separated arms 5 whose ends form bearing elements in which the tractor elements 6 are 45 revolvably mounted in any suitable manner.

As shown more clearly in Figs. 3 and 4, the tractor elements 6 comprise wheels having paddles or buckets 7 to which lateral disk-like members 8 are secured in any suitable manner. These disk-like members 8 are provided 50 with teeth 9 at their peripheries, but these

teeth 9 are not essential for the operation of the invention. These teeth 9 may be of various shapes and they operate as root-cutters, that is, to cut away any incrustations or deposits upon the wall of the sewer or pipe which is being cleaned. By tractor means or elements we mean a device or devices which positively impel the nozzle, as distinguished from the reaction produced by a rearwardly 55 deflected body of water.

The vanes or buckets 7 may be curved as shown in Fig. 4, or they may be straight as shown in Fig. 3.

As shown in Fig. 2, the inner or adjacent 70 ends of the tractor elements are quite close to each other, so as to define a passage 10 which is substantially triangular in configuration. The opening or openings 11 in the nozzle 1 may be of any desired shape and dimensions and, for example, there may be an opening 11 corresponding to the inner portion of each tractor element adjacent the passage 10, so that each tractor element is caused to turn when water is forced out of the 80 nozzle 1.

The operation of this device is as follows:—

When the nozzle is introduced into a pipe or sewer to be cleaned, the weight thereof 85 causes the said nozzle to rest upon two of the tractor elements 6. When the water is forced through and out of the nozzle 1, the tractor elements 6 are positively turned so that they act as propelling wheels to positively force 90 the nozzle forward.

The drawings herein are not according to scale and the illustration is diagrammatic.

According to this invention, it is not necessary that any substantial amount of the water 95 forced into the nozzle 1 should be rearwardly deflected by means of vanes, cups or the like in order to forwardly propel the device. While a portion of the water can be forced out of the nozzle in a lateral direction, the 100 amount of this lateral stream of water can be regulated to any desired extent.

A preferred embodiment of this invention has been shown, but it is clear that numerous changes and omissions could be made without 105 departing from its spirit.

Claims:

1. A pipe cleaning device comprising a nozzle adapted to have a body of water forced through and out therefrom, and tractor means associated with the said nozzle and adapted to be positively impelled by the 110

movement of said body of water, said tractor means being adapted to engage the inner wall of the pipe.

2. A pipe cleaning device comprising a nozzle adapted to have a body of water forced through and out therefrom, and revoluble tractor means provided with vanes adapted to be impelled by the said moving body of water, the said tractor means being connected 10 to the nozzle, said tractor means being adapted to engage the inner wall of the pipe.

3. A pipe cleaning device comprising a nozzle having a plurality of paddle wheels associated with the front end thereof, the said 15 nozzle being adapted to have a body of water forced through and out therefrom, the said nozzle being open adjacent the inner peripheries of the said paddle wheels.

4. A pipe cleaning device comprising a nozzle adapted to have a body of water forced 20 through and out therefrom, tractor means associated with said nozzle and adapted to be positively impelled by the movement of said body of water, and cutting means forming part of the said tractor means.

5. A pipe cleaning device comprising a nozzle having a paddle wheel associated with the front end thereof, the said paddle wheel having a disk member extending substantially to the periphery thereof, the periphery of said disk member being provided with cutting means.

In testimony whereof we affix our signatures.

LEE R. TITCOMB.
